BOWL HOLDER AND SHANK FOR A SMOKER'S PIPES

Jerome Gevirman, Brooklyn, N. Y.

Application January 30, 1956, Serial No. 39,958

Term of patent 14 years

(Cl. D85—8)

Fig. 1

Fig. 3

Fig. 1 is a top plan view of a bowl holder and shank for a smoker's pipes, showing my new design;

Fig. 2 is a bottom plan view thereof; and

Fig. 3 is a side elevational view thereof.

I claim:

The ornamental design for a bowl holder and shank for a smoker's pipes, as shown.
